UNITED STATES PATENT OFFICE.

CHARLES EDWARD HOPKINS, OF EMILIE, PENNSYLVANIA.

GAME OF CARDS.

1,287,317.

Specification of Letters Patent. Patented Dec. 10, 1918.

Application filed November 17, 1917. Serial No. 202,525.

To all whom it may concern:

Be it known that I, CHARLES EDWARD HOPKINS, a citizen of the United States, residing at Emilie, in the county of Bucks and State 5 of Pennsylvania, have invented a new and original Game of Cards, titled Capture the Kaiser, composed of a pack of cards played as herein described and shown on drawings of designs used on cards played with in the 10 game and forming a part thereof.

Capture the Kaiser.

A game played with forty-five cards, ten cards in each suit. In the preferred embodiment of my invention one suit is to represent the army, comprising a general, a colonel, a lieutenant and seven cards with a bust of a soldier on each, body of card to show tents and sky. One suit to represent the navy 15 comprising an admiral, a captain, a lieutenant and seven cards with a bust of a sailor on each card and a warship, body of card to represent sky and water. One suit to 20 represent the aeroplane service comprising a general, a colonel, a lieutenant and seven cards with aeroplane and bust of aviator on each, body of card to represent clouds. One 25 suit to represent submarine service comprising an admiral, a captain, a lieutenant and seven cards with a submarine and bust of 30 sailor on each card, body of card to represent sky and water. The suits from one to seven inclusive, to denote the numbers one to seven in order to establish relative numbers. The relative values of the different 35 suits are the same, it being understood however, that the first suit card played elects the suit to which said card belongs as the trump. One card to represent the Hand of 40 Fate.

One card to represent money, to be the card of Finance.

One card to represent a diplomat, the card of Diplomacy.

45 One card to represent secret service, the Secret Service card.

One card representing the Kaiser.

The object of the game is to capture the Kaiser, either by the Hand of Fate, by 50 the Army, by the Navy, by the Aeroplanes, by the Secret Service, by Finance, by Diplomacy or by Submarines.

The Hand of Fate card is to have hour

glass in center, body of card to represent clouds with hands pointing toward hour 55 glass.

The card of Finance to represent gold flowing from bags.

The card of Diplomacy to have a bust of person to represent a diplomat, the body of 60 card to represent documents.

The Secret Service card to have a bust of person with a mask on face, body of card to be masks.

The card representing the Kaiser to have 65 a bust of Kaiser holding a broken crown on his head, the body of the card to be covered with broken crowns.

The designs on all cards to be arranged so that either end of the cards will show 70 the above mentioned designs.

The back of all the cards to have the word War, cover the surface.

The case to hold the cards to bear the title, Capture the Kaiser. 75

The game.

Capture the Kaiser.

The game is played with a deck of forty- 80 five cards.

For two, three, four, five, six, seven or eight persons, according to direction.

The pack.

The pack consists of forty-five cards. For 85 two hands, the six and seven of each suit are discarded. Each player has eighteen cards and one turned down on center of table. Three hands, the seven of Aeroplane and the seven of Submarine cards are discarded. 90 Each player has fourteen cards and one turned down on center of table.

Four hands, each player has eleven cards and one turned down on center of table.

Five hands, are played with two decks, 95 the seventh card of each suit being discarded and one Kaiser. Each player has sixteen cards and one turned down on center of table.

Six hands are played with two decks, the 100 sixth and seventh card of each suit and one Kaiser is discarded. Each player having twelve cards and one turned down on center of table.

Seven hands are played with two decks, 105 the sevens of Aeroplane and the sevens of

Submarine and one Kaiser are discarded. Each player having twelve cards and one turned down on center of table.

Eight hands are played with two decks, 5 discarding one Kaiser, each player having eleven cards and one turned down on center of table.

Dealing.

- 10 The deal to be decided each time by cutting the cards. If the Hand of Fate is cut, it always wins the deal. The Finance card, the Diplomat and Secret Service cards have no value in cutting, persons cutting them 15 lose chance to deal. The highest card of any suit wins the deal. Four cards are always dealt to each player, the next card is always placed face down on center of table, and the remaining cards are dealt according 20 to number of cards used. Partners play opposite each other. Player to right of dealer cuts cards. Cards are dealt to left of dealer, who do not lose deal because of mis-deal. If cards are exposed players can call to have 25 cards dealt over.

Playing the game.

Player to left of dealer always leads. A suit must be led on the first lead, and the 30 winner of the first trick must discard a card and in its place, take up card from center of table. The suit led on first trick played is trump throughout the game. Trump or other cards are beaten at any time 35 by the Hand of Fate, which card takes any trick at any time so desired. The Finance, the Diplomat and Secret Service cards can be played at any time instead of trump or suit, otherwise suit or trump must be played 40 throughout the game. The Finance, the Diplomat and Secret Service cards are higher than any suit or trump only when led. Whichever card is played first has precedence over the other cards, as the Finance, Diplomat and Secret Service cards are 45 of equal value, and any card can be played upon them. If the Hand of Fate is led, trump must be played upon it. The Kaiser cannot be discarded or played upon any 50 trick, but must be captured in the last trick by the highest card played.

Value of cards.

The Hand of Fate is always the high 55 card. The rank of any suit is high; from highest officer to lowest number on any suit. The Finance card, the Diplomat and Secret Service cards are of equal value, and are higher than any suit or trump, only when 60 played first or led.

The score.

One hundred points constitutes the game. Any player or partner scoring one hundred

points, can call the game at any time. Calling the game and not having one hundred points, the player or partners doing so, loses all points made during the deal at that time. Each trick taken counts one point. To capture the Kaiser counts ten points. 70

The invention is illustrated by the drawings submitted as follows:

Figure 1 is a view of the General of the Army suit.

Fig. 2 is a view of the Colonel card of the 75 Army suit.

Fig. 3 is a view of the Lieutenant card of the Army suit.

Fig. 4 is a view of a soldier card of the 80 Army suit.

Fig. 5 is a view of the General card of the Aviation suit.

Fig. 6 is a view of the Colonel card of the Aviation suit.

Fig. 7 is a view of the Lieutenant card of 85 the Aviation suit.

Fig. 8 is a view of the Aviator card of the Aviation suit.

Fig. 9 is a view of the Admiral card of the 90 Navy suit.

Fig. 10 is a view of the Captain card of the Navy suit.

Fig. 11 is a view of the Lieutenant card of the Navy suit.

Fig. 12 is a view of the Sailor card of the 95 Navy suit.

Fig. 13 is a view of the Admiral card of the Submarine suit.

Fig. 14 is a view of the Captain card of the Submarine suit.

Fig. 15 is a view of the Lieutenant card of 100 the Submarine suit.

Fig. 16 is a view of the Sailor card of the Submarine suit.

Fig. 17 is a view of the Diplomat card. 105

Fig. 18 is a view of the Finance card.

Fig. 19 is a view of the Secret Service card.

Fig. 20 is a view of the Hand of Fate card.

Fig. 21 is a view of the Kaiser card.

Fig. 22 is a view of the back of the cards of all of the above suits and cards.

It will be gathered from the foregoing that in addition to suit cards representing the four arms of the army and navy of a 115 country, my game cards comprise a "Kaiser" card that constitutes a quarry, a Hand of Fate, card that is always superior in value to any other card, and three sub-superior cards denominated Diplomat card, Finance 120 card, and Secret Service card, respectively, and each of which when led is superior to any other card save the superior Hand of Fate card. The card constituting the quarry and the three sub-superior cards alluded to 125 serve in conjunction with the superior card and the suit cards described to make the game played with the cards an exemplifica-

tion of the existing international war, and in that way increase the pleasurable interest excited by the playing of the game.

Having described the invention, I claim
5 as new.

A pack of game cards comprising suits representing different arms of the armed service of a country, each suit including
10 cards of consecutively increasing values; a card that constitutes a quarry; a card typi-

fying Fate as the most important factor in the existing international war, and that, in play, is always superior to every other card; and three sub-superior cards typifying Diplomacy, Finance and Secret Service,
15 respectively, and that in play are superior to every other card save the superior card.

In testimony that I claim the above game as my own, I affix my signature.

CHARLES EDWARD HOPKINS.

Copies of this patent may be obtained for five cents each, by addressing the "Commissioner of Patents,
Washington, D. C."
